(57) **CLAIM**

I claim the ornamental design for a combined tanning module and dressing room, as shown and described.

DESCRIPTION

FIG. 1 is a top view of a tanning module and connecting dressing room showing my new designs.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a bottom view thereof; and,

FIG. 7 is a top isometric view thereof.
